CLAIM

The ornamental design for a four-sided tent as shown and described.

DESCRIPTION

FIG. 1: is a front view of the four-sided tent;

FIG. 2: is a back view of the four-sided tent;

FIG. 3: is a left-hand side view of the four-sided tent;

FIG. 4: is a right-hand side view of the four-sided tent;

FIG. 5: is a top view of the four-sided tent; and,

FIG. 6: is a bottom view of the four-sided tent.

The broken lines included in FIGS. 1 through 6 show portions of the tent that form no part of the claimed design.

1 Claim, 6 Drawing Sheets
